UNITED STATES PATENT OFFICE

ALBERT C. TOTZKE, OF ST. JOSEPH, MICHIGAN.

FASTENER-APPLYING MACHINE.

1,258,275.

Specification of Letters Patent.

Patented Mar. 5, 1918.

Application filed July 29, 1916. Serial No. 111,989.

To all whom it may concern:

Be it known that I, ALBERT C. TOTZKE, a citizen of the United States of America, and resident of St. Joseph, Berrien county, Michigan, have invented a certain new and useful Improvement in Fastener-Applying Machines, of which the following is a specification:

My invention contemplates a machine for use in fastening grapevines to the heavy wires which are strung on posts and ordinarily employed in vineyards for supporting the vines.

The object of my invention is, therefore, to materially reduce the amount of time and labor necessary to fasten the vines to the wires or other supports.

To this and other useful ends, my invention consists in matters hereinafter set forth and claimed.

In the accompanying drawings:

Figure 1 is a side elevation of a machine for use in fastening grapevines to the wires which are supported on posts, said machine embodying the principles of my invention.

Fig. 2 is a bottom plan view of said machine.

Fig. 3 is a longitudinal section of said machine.

Fig. 4 is a section on line 4—4 in Fig. 3.

Fig. 5 is a detail view of the device for feeding the wire from which the staples are made.

Fig. 6 is a view similar to Fig. 4, but showing the parts in the positions which they occupy at the moment the short length of wire is clenched around the grapevine and the heavy wire which forms the support.

Fig. 7 is a vertical section on line 7—7 in Fig. 3.

Fig. 8 is a perspective of a length of grapevine and the heavy wire to which the same is attached, showing three of the staples which have been driven and clenched around the vine and heavy wire.

Fig. 9 is an enlarged cross-section of the vine and the heavy wire forming a support therefor, showing the manner in which the staple is bent and clenched around the same.

As thus illustrated, my invention comprises a metal body A which is attached at one end to a cross-bar B, the latter having a strap C by which the said bar can be fastened to the waist. This arrangement (the bar B and belt C) prevents the machine

from tilting sidewise. The body A has a removable side-plate D, and inside of said body a staple-driver E is arranged to reciprocate back and forth, in the manner of an ordinary stapling machine. This driver has its forward end-portion e arranged to reciprocate between the two prongs or side-ports 1 of the staple-former F, which latter is connected by a rod f with the block 2 carried by the rear end-portion of the staple-driver. A compression-spring 3 is applied to said rod f, and the said driver is provided with ratchet-teeth 4 which engage the teeth of the segment 5, the latter being journaled on the body at 6 and provided with a crank-handle G, which extends downwardly when the device is in use and by which the said driver E can be reciprocated back and forth by operating said handle. The front end of the body A is provided with a transverse slot or notch H to receive the grapevine 7 and the heavy wire 8 to which the vine is to be secured. The closed end of this slot forms a stop to hold the vine and support in alinement with the mechanism, so that the staple will be driven accurately and not at one side of said vine. Opposite to said driver-portion e is an anvil or clench-block h against which the heavy wire and the grapevine are held during the operation of fastening them together. The pivoted latch I is carried by the rear portion of the driver E and is controlled by a spring i to cause it to engage the corner 9 of the staple-former F, so that the driver and former are locked together during the first part of the forward movement of the driver. As soon as the cam-portion 10 of said latch strikes the stationary cam 11, the staple-former F is then unlocked from the staple-driver E, and the staple-driver then moves forward alone. The wire 12 is fed through a tube J across the path of the staple-former portions 1, by the feed-rolls j, which latter are actuated by the dog K which engages the ratchet-wheel 13 on the axis of one of said rolls, preferably the larger one, so that the wire is fed into position when the staple-driver E moves backward. To produce the correct feeding action, the dog K is provided with a slot k for the pin 14 on the block 2, whereby the initial forward movement of the driver E does not produce any movement of this dog; but the latter has fresh tooth-engagement with the ratchet-wheel before the staple

2

driver completes its forward stroke, so that when the staple-driver moves backward its final movement in this direction is accompanied by the actuation of the feed-rolls to feed a length of wire into position for the next staple. It will be understood, however, that the devices for feeding the staple-wire may be of any suitable known or approved character.

10 As stated, the machine is strapped around the waist of the operator, with the handle G downward, as shown in Fig. 1, and this handle is operated by the right hand while the left hand is used for guiding the grape-vine and heavy wire through the slot H, in a manner that will be readily understood. When the handle is pulled backward, the staple-driver and staple-former move forward, causing the bifurcated end of the 15 staple-former to cut off a length of the wire 12. The wire feeds through the slot 15 of the loop-bar 16, which latter is movably mounted on the plate D by means of a spring 17, attached thereto at its rear end, 20 whereby said loop-bar may move outwardly in the manner shown in Fig. 6, when the staple-driver portion e is thrust against the bevel 18 of said loop-bar. The forward motion of the staple-former F causes the prongs 30 1 to coöperate with the loop-bar 16 which they then embrace to bend the cut-off piece of wire into the form of a staple, and this staple is then caused to straddle the grape-vine 7 and the heavy wire 8, and the ends 35 of the staple are then bent toward each other and clenched around the grapevine and heavy wire, by the anvil h, which is suitably shaped for this purpose, in the manner shown in Figs. 6, 8 and 9, so that the 40 staple is converted into a ring which encircles the grapevine and the heavy wire by which it is supported. When the handle G is then pushed forward, the staple-forming mechanism is returned to normal position, 45 as shown in Fig. 3, and at this time a fresh length of wire 12 is fed into position for the next staple. Thus the operator works the machine with one hand and manipulates the grapevine with the other.

50 It will be seen, therefore, that by my invention I provide a machine which will do the work heretofore ordinarily done by hand. Usually, the grapevines are tied to the heavy trellis-wires by twine or other 55 flexible means, and the work is slow and somewhat laborious. Furthermore, the twine becomes weakened by the weather and falls off and allows the grapevine to become loose. By means of my invention, 60 however, it is possible to secure the vines in place by galvanized or copper or other suitable wire which will last for a considerable length of time. In addition, the time and labor are materially reduced.

65 The slot H formed in the head of the

machine is closed at its upper end, so that a shoulder 19 (formed by the edge of the plate D) is provided which can rest on the heavy wire 8 between operations, and while the staple is being driven and clenched, or while the operator slides the machine along the said wire to apply successive fasteners to the vine. Thus the shoulder 19 forms a gage to accurately position the wire and vine in the slot, this shoulder being at one 75 side (see Figs. 2 and 3) of the center of the clench-block h, and the lower edge of the shoulder accurately limiting the upward insertion of the wire and vine in the slot, so that the staples will be properly driven. 80 But the bottom of this slot is open to receive the vine and the wire 8, or other support, by lateral insertion (insertion by relative movement which is in a direction transverse of the vine and support when held 85 parallel, or substantially parallel, and also transverse of the machine) of the vine and support in the open end of the slot, in a manner that will be readily understood.

I do not limit myself to the exact construction shown and described.

What I claim as my invention is:—

1. A portable machine adapted to be manipulated as a tool for fastening vines to supports, comprising a head provided with means for receiving and holding in place the vine and the support to which it is to be secured, and mechanism coöperating with said means for bending and then clenching the ends of a length of wire around the vine and support, said means consisting of a vertical slot which is open at its lower end to receive the vine and support, said mechanism including a staple-former and driver at one side of said slot and a fixed anvil at 95 the other side thereof to engage and bend the ends of the staple around the vine and support, the upper end of said slot being closed to rest on said support.

2. A portable machine adapted to be manipulated as a tool for fastening vines to supports, comprising a head provided with means for receiving and holding in place the vine and the support to which it is to be secured, by lateral insertion of both the 110 vine and the support in said head, and mechanism coöperating with said means for bending and then clenching the ends of a length of wire toward each other and around the vine and support, said means 115 having a stationary anvil against which the ends of the wire in staple form are driven by said mechanism, so that the vine and support are held in engagement by the same 120 encircling portion of wire.

3. A portable machine adapted to be manipulated as a tool for fastening vines to supports, comprising a head provided with means for receiving and holding in place the vine and the support to which it is to 125

be secured, and mechanism coöperating with said means for bending and then clenching the ends of a length of wire around the vine and support, said means consisting of 5 a transverse slot which is open at its outer end to receive the vine and support, said mechanism including a staple-former and driver at one side of said slot and a fixed anvil at the other side thereof to engage 10 and bend the ends of the staple around the vine and support, the inner end of said slot being closed to limit the lateral insertion 15 therein of said vine and support.

4. The said machine, as stated in claim 2, 15 in which said means include a shoulder to

rest the machine on said support during the operation.

5. The said machine, as stated in claim 3, in which the closed end of said slot forms a shoulder to rest the machine on said support during the operation. 20

6. The said machine, as stated in claim 3, in which means are provided to automatically feed wire parallel with said slot to said mechanism, the staple-former being 25 disposed in the plane of said slot.

Signed by me at St. Joseph, Mich., this 22d day of July, 1916.

ALBERT C. TOTZKE.
